UNITED STATES PATENT OFFICE

2,138,949

FLIGHT RETARDER FOR AIRSHIPS

Fred Weidman, Detroit, Mich.

Application May 8, 1937, Serial No. 141,462

6 Claims. (Cl. 244—113)

My invention relates to flight retarders or brakes for airships of the character described in the patent to John C. Hasbrouck, Junior, No. 1,274,037, issued July 30, 1918, in which pairs of 5 brake elements have their rear edges hinged at opposite sides of the body or fuselage and their front edges free to move outwardly to a position normally flush with the sides of the body, the said elements being provided with means for 10 manual movement by the operator so as to produce various degrees of braking action upon the forward movement of the ship.

In the patent above referred to, upper and 15 lower vent valves are also provided rearwardly of the braking elements whereby the air pressure on said elements is relieved through top and bottom openings in the fuselage. It is found, however, that further relief of the air pressure is sometimes necessary, and it is the object of this 20 invention to provide a device, either automatically or manually operated, whereby such relief is afforded.

With this object in view, a preferred embodiment of my said invention will now be described 25 with reference to the accompanying drawing, in which—

Figure 1 is a sectional plan view showing the rear end of an airplane having my invention applied thereto.

Figure 2 is a fragmentary side elevation of the 30 same.

Figure 3 is a sectional plan view of a brake retarding element illustrating one method of relieving the air pressure from the same.

Figure 4 is a transverse section taken on line 35 4—4 of Figure 3.

Figure 5 is a sectional plan view corresponding to Figure 3 showing a modified form of relief device, and

Figure 6 is a transverse section taken on line 40 6—6 of Figure 5.

Like characters designate corresponding parts throughout the several views.

Referring more particularly to Figures 1 to 4 of 45 the drawing, A designates the flying machine body and 3 are adjustable elevating planes, while 4 indicates a rudder, the said planes and the rudder being operated in the manner well known in the art. The numerals 5 designate a pair of drag 50 elements or fins disposed at opposite sides of the body with their rear edges 6 hinged to the body and their front edges free. Suitable spring means 7 operate on each of the drag elements 5 to swing the latter outwardly from a closed position flush 55 with the sides of the body. These elements are

adapted to be drawn inwardly to the closed position by any suitable means such as cables 8 which cross each other at 9 and pass over guide pulleys 10 and thence forwardly to suitable manually operated levers, not shown.

To facilitate the closing or complete retraction of the brake elements 5, there are provided upper and lower openings 14 in the body which are adapted to be closed by swinging vent valves 15 hinged at their forward edges 16 to the body, 10 suitable spring means being employed to assist in the opening of the vent valves and cables or other means being provided whereby the said valves may be closed by the operator. These manually operated means are not herein shown since they 15 are fully described in the patent above referred to.

In one method of affording the additional relief, which is the object of the present invention, there is provided in each of the retarding elements 5 an opening 51 which is normally closed by a series of 20 louvres or flaps 52, each of which is hinged at 53 and provided with springs 54 which tend normally to maintain the said flaps in the closed position. It will be understood that excessive pressure upon the inner faces of the elements 5 will tend to open 25 the said flaps 52 to a greater or less degree against the action of the springs 54, but in some cases I may provide a series of levers 55 shown in broken lines upon the flaps which are connected by a cable 55', whereby they are simultaneously 30 opened by pulling on the said cable which passes over a guide pulley 56 and forwardly to a point proximate the operator's seat.

In the modification shown in Figures 5 and 6, there is employed, instead of the flaps or louvres 35 52 a gate 57 slidably mounted in grooves 58 in the upper and lower edges of the opening 51, the said gate being normally kept closed by means of a spring 59 and opened to the required degree by the cable 60 which passes over a guide pulley 61 40 and forwardly to a point within reach of the operator, as will be understood.

It will be observed from the foregoing description and by reference to the drawing that I have provided a device which is simple in construction 45 and well adapted to the purpose intended, and while I have herein described and shown preferred embodiments of my said invention, it will be readily understood by those skilled in the art to which the same relates that various changes in 50 detail may be made to suit any particular or peculiar requirement without departing from the spirit of my invention as defined in the appended claims.

Having thus described my said invention, what 55

I claim and desire to secure by Letters Patent of the United States is:

1. An airship including a body, means for propelling and sustaining the same, brake elements arranged on opposite sides of the body with their rear edges hinged thereto and their front edges free to move outwardly from and inwardly to a position flush with the sides of the body, upper and lower vent openings located between said brake elements and adapted to be closed by flaps hinged to said body by their forward edges, and auxiliary vent means located within said brake elements. 5
2. An airship including a body, means for propelling and sustaining the same, brake elements arranged on opposite sides of the body with their rear edges hinged thereto and their front edges free to move outwardly from and inwardly to a position flush with the sides of the body, upper and lower vent openings located between said brake elements and adapted to be closed by flaps hinged to said body by their forward edges, auxiliary vent means located within said brake elements, and means for opening and closing said auxiliary vent means. 10
3. An airship including a body, means for propelling and sustaining the same, brake elements arranged on opposite sides of the body with their rear edges hinged thereto and their front edges free to move outwardly from and inwardly to a position flush with the sides of the body, upper and lower vent openings located between said brake elements and adapted to be closed by flaps hinged to said body by their forward edges, auxiliary vent means located within said brake elements, and resilient means adapted to normally 15
4. An airship including a body, means for propelling and sustaining the same, brake elements arranged on opposite sides of the body with their rear edges hinged thereto and their front edges free to move outwardly from and inwardly to a position flush with the sides of the body, upper and lower vent openings for reducing the pressure on the brake elements, means for closing 20 said vent openings, and auxiliary vent openings in said brake elements. 5
5. An airship including a body, means for propelling and sustaining the same, brake elements arranged on opposite sides of the body with their rear edges hinged thereto and their front edges free to move outwardly from and inwardly to a position flush with the sides of the body, upper and lower vent openings for reducing the pressure on the brake elements, means for closing 25 said vent openings, auxiliary vent openings in said brake elements, and valve means for closing said last-named openings. 20
6. An airship including a body, means for propelling and sustaining the same, brake elements arranged on opposite sides of the body with their rear edges hinged thereto and their front edges free to move outwardly from and inwardly to a position flush with the sides of the body, upper and lower vent openings for reducing the pressure 30 on the brake elements, means for closing said vent openings, auxiliary vent openings in said brake elements, valve means for closing said last-named openings, and resilient means adapted to normally retain said valve means in closed 35 position. 30

FRED WEIDMAN.
